(57) **CLAIM**

The ornamental design for a closure for a water filter, as shown.

DESCRIPTION

FIG. 1 is a perspective view of the cap for a closure for a water filter in accordance with the present invention.

FIG. 2 is a top view of the cap of FIG. 1.

FIG. 3 is a left side view of the cap of FIG. 1.

FIG. 4 is a right side view of the cap of FIG. 1.

FIG. 5 is a bottom view of the cap of FIG. 1.

FIG. 6 is a front view of the cap of FIG. 1; and,

FIG. 7 is a back view of the cap of FIG. 1.

The broken line showing of a water filter is included for the purpose of illustrating and forms no part of the claimed design.
